CONVERTIBLE BAG AND APRON

Richard K. Peek, Kansas City, Mo., assignor to
Percy Kent Bag Co., Inc., Kansas City, Mo.

Application March 29, 1948, Serial No. 17,663

4 Claims. (Cl. 150—1)

1

This invention relates broadly to the manufacture of containers in the form of bags, particularly those made from relatively strong fabric. The primary aim being to produce a novel bag that is easily transformable into an article of use such as an apron, after the bag has been emptied and the same laid open to a relatively flat extended condition.

It is common knowledge, particularly in the field of stock feeds, flour and the like, that sales are increased substantially when the bags containing the sold product are made from fabrics having suitable colors and designs formed therein, since the ultimate consumer may then utilize such bags by converting the same into articles of clothing, curtains, table cloths and the like. This present day universal practice has become quite popular in this particular trade and retailers and wholesalers alike agree that sales are substantially enhanced thereby.

It is the most important object of this invention, therefore, to advance a step further by not only forming the bags from a fabric material having the variable colors of the design pre-formed therein, but also having a suitable article of merchandise such as clothing prefabricated and ready for use after the bag is emptied, cleaned and the temporary stitching thereof removed.

Another important object of this invention is the provision of a cloth bag having temporary stitching readily removable along at least three edges thereof, said bag presenting an apron when the said stitching is removed and the bag laid open, ready for use.

A further object of this invention is to provide a bag formed from a single piece of fabric folded upon itself along a medium line to present a pair of facing panels, each of which has hemps preformed along certain edges thereof and a tie tape threaded through one of the hemps for attaching the same in the form of an apron to the body of a wearer when the bag is disassembled with respect to stitching temporarily holding the panels together.

Other objects of this invention include the particular disposition of the aforesaid hemps, the way in which the temporary chain stitch is formed on the bag, the way in which the tying tapes are disposed so as not to interfere with the function of the bag itself, and many more minor details, all of which will be made clear as the following specification progresses.

In the drawing,

Figure 1 is a side perspective view of a combination bag and apron, made in accordance with the present invention.

Fig. 2 is a side elevational view thereof, showing the same laid open in the form of an apron.

Fig. 3 is a cross-sectional view taken on line

2

III—III of Fig. 1, looking in the direction of the arrow.

Fig. 4 is a cross-sectional view taken on line IV—IV of Fig. 1, looking in the direction of the arrows; and

Fig. 5 is a fragmentary cross-sectional view taken on line V—V of Fig. 2.

The bag per se shown in Fig. 1 of the drawing may either be formed by a pair of opposed facing panels, or as illustrated, from a single piece of material folded upon itself on a medium line 10 to present a pair of panels 12 and 14. This folding construction is quite conventional and obviously the preferred form of producing bags of this character. When these panels 12 and 14 are so folded and in relative face-to-face relationship, the edges thereof are all contiguous and held together by lines of stitching 16, 18, and 20. This stitching is of the readily removable type such as the usual chain stitch. Ordinarily the lines of stitching 16 and 18 are formed in the bags at the time of manufacture and the line of stitching 20 sewed along the normally uppermost edge of the bag after the same has been filled with flour, feed or like material. Before the panels 12 and 14 are folded to the condition shown in Fig. 1, the single piece of material has two of its opposed edges folded upon itself to present hemps 22 and 24. These hemps that are clearly illustrated in Fig. 3 are held by lines of permanent stitching 26 and 28.

Also, before folding of the single piece of material to the bag forming condition, one end thereof is folded upon itself in the manner illustrated in Fig. 5 of the drawing and a pair of spaced-apart lines of permanent stitching 26 and 28 are formed therealong. This stitching 26 and 28 presents a pair of loops 30 and 32. An elongated tying tape of double thickness and having a longitudinal marginal line of permanent stitching 34 is preformed and threaded into the loop 32. This tying tape, designated by the numeral 36, is longer than the width of the piece of material forming panels 12 and 14 and has its ends extending therebeyond and from the loop 32 at each end thereof in the manner illustrated in Fig. 2.

If desired, this tying tape 36 may be tacked to the panels 12 and 14 to prevent slipping therefrom.

After the piece of flexible material has been so formed with the hemps 22 and 24, the loops 30 and 32, and the tie tape 36 in place, the above described folding takes place to present the panels 12 and 14. The lines of chain stitching 16 and 18 are then sewed to join together the proximal marginal edges of the panels 12 and 14. It is noted, both in Figs. 1 and 3, that the stitching 18 is disposed inwardly from the hemps 22 and 24 and the permanent stitching 26 and 28 form-

ing such hems. Obviously, this line of stitching 18 could be disposed to join together the hems 22 and 24, but since these hems are relatively narrow, a stronger and more desirable bag is presented by having this line of stitching 18 disposed slightly inwardly from the proximal edge of the bag.

The lowermost edge of 38 of the initially flat body may have a hem formed thereon if necessary, but ordinarily this edge constitutes a permanent uncut, selvage portion of the material from which the bag is formed. Accordingly, the line of stitching 20 which is placed on the bag after the same has been filled may be positioned quickly and easily without the necessity of any concern as to interference with other permanent stitching, hems or loops.

As illustrated in Figs. 1 and 4, the line of stitching 16 along the bottom of the bag and along the top of the apron joins together the loops 30 of the panels 12 and 14. Four thicknesses, therefore, are presented at the bottom of the bag and consequently an extremely strong construction is presented.

When the bag is formed in the manner illustrated in Fig. 1, the ends of the apron tie-tape 36 are tied together to present a bow 40. This bow 40 does not interfere with the normal use of the bag, adds a novel overall appearance thereto and readily suggests to the purchasing public the purpose of the bag after its normal use has been completed.

It is clear from the foregoing that after the bag has been emptied, the owner thereof may easily and quickly remove the chain stitching 16, 18, 20 and 22 whereby the panels 12 and 14 may be laid open to the condition illustrated in Fig. 2.

The openings caused by the stitching 16, 18, and 20 have been shown in Fig. 2 as at 42 exaggerated in size, but in normal use such openings would not be readily visible or have any effect upon the appearance of the apron.

After such chain stitching has been removed, it is apparent that the apron is ready for use by simply washing, or otherwise cleaning, if necessary.

An attractive appearance is presented along the top of the apron because of the disposition of the tie tape 36 inwardly from the top edge thereof and because of the extended loop portion 30, as shown in Fig. 2. This uppermost edge may be gathered before the apron is placed in use in the usual manner.

It is also to be understood that the fabric from which the panels 12 and 14 is made shall have various designs formed therein and be of many and varied attractive colors.

Very little advertising will be necessary, because the consuming public will soon become aware of the novel construction of the bag and the simple way in which the same can be converted to a useful article of merchandise.

While only one modification of the present invention has been illustrated and described, it is readily apparent that articles other than aprons may be preformed in the material from which the bag is made, without departing from the spirit of this invention as defined by the appended claims.

Having thus described the invention, what is claimed as new and desired to be secured by Letters Patent is:

1. A bag readily convertible to an apron, said

bag comprising a pair of identical panels disposed in face-to-face relationship and formed from a single piece of flexible material folded upon itself to present one edge of the bag; quickly removable stitching joining all proximal marginal edges of said panels; and means on the both panels for attaching the same to the body of a wearer when all of said stitching is removed and the panels laid open and unfolded in an apron-forming condition.

2. A bag readily convertible to an apron, said bag comprising a pair of substantially identical panels disposed in face-to-face relationship and formed from a single piece of flexible material folded upon itself to present one edge of the bag; quickly removable stitching joining proximal marginal edges of said panels; and means on the panels for attaching the same to the body of a wearer when said stitching is removed and the panels laid open in an apron-forming condition, certain of said edges of the panels having a hem permanently formed thereon, said stitching joining certain of the hems.

3. A bag readily convertible to an apron, said bag comprising a pair of substantially identical panels disposed in face-to-face relationship and formed from a single piece of flexible material folded upon itself to present one edge of the bag; quickly removable stitching joining proximal marginal edges of said panels; and means on the panels for attaching the same to the body of a wearer when said stitching is removed and the panels laid open in an apron-forming condition, certain of said edges of the panels having a hem permanently formed thereon, the hem formed on one edge of the panels extending from said folded edge of the bag forming a loop, said means comprising a tying tape threaded into said loop.

4. A bag readily convertible to an apron, said bag comprising an initially flat fabric piece folded upon itself along a median line to present a pair of facing panels, the fold constituting one edge of the bag; temporary stitching adjacent the remaining edges of the bag and joining the panels; permanently stitched hems formed at the edge of each panel opposite to said fold; one of the other edges of each panel being rebent upon itself; a pair of spaced rows of permanent stitching joining the rebent portions to corresponding panels to present a pair of loops; and a tying tape passing through the innermost loop for attaching the panels to a wearer's body when said temporary stitching is removed and the panels laid open.
